UNITED STATES PATENT OFFICE.

CHARLES C. BLAKE, OF BROOKLINE, MASSACHUSETTS.

METHOD OF SECURING SOLES TO LAST-BOTTOMS.

1,365,221.

Specification of Letters Patent. Patented Jan. 11, 1921.

Application filed September 16, 1915. Serial No. 51,099.

To all whom it may concern:

Be it known that I, CHARLES C. BLAKE, a citizen of the United States, residing at Brookline, in the county of Norfolk and 5 State of Massachusetts, have invented a new and useful Improvement in Methods of Securing Soles to Last-Bottoms, of which the following is a specification.

The present invention relates to the manufacture of boots and shoes.

In the manufacture of shoes the insoles of welt shoes and the better grades of McKay shoes, and the outsoles of turn shoes, are secured to the lasts used in the shoe bottoming operations by tacks driven deeply into the bottoms thereof. The use of these tacks greatly damages the lasts, requires separate operations for their insertion and removal, and necessitates the services of a reliable 10 inspector to insure that all the sole tacks are removed. Usually the soles are secured to the lasts by a few tacks driven along the median line of the sole. This practice makes it difficult for the sole to conform to 15 the bottom of the last. Moreover, as the margin of the sole is free, special precautions must be taken to prevent it from buckling under the strains of the pulling-over and lasting operations. These precautions 20 usually take the form of a sole-rest for engaging the margin of the sole near the operating point, of mechanism for actuating the pulling-over or lasting pincer during the updraw movement in a direction 25 slightly away from the edge of the sole so as to prevent the upper from dragging over the edge of the sole and thus causing the margin of the sole to buckle, or of special last constructions. Furthermore it is necessary 30 to fill the holes made in the sole by the sole tacks with rubber cement if it is desired to prevent the seepage of water therethrough and the consequent wetting of the wearer's feet. Obviously the use of tacks 35 for securing soles to the bottom of shoe lasts seriously affects the cost of making 40 shoes.

One object of the present invention is to provide a simple, cheap and effective 45 method of securing the soles to the bottom of the lasts.

To the accomplishment of this object a feature of the present invention contemplates the cementing of the sole to the bottom 50 of the last. By this method the use of

tacks is obviated, the sole readily conforms to the shape of the last bottom, the sole is not perforated, and all danger of the sole buckling under the strains of the lasting operation is avoided without the aid of additional mechanism or apparatus.

Broadly considered merely the margin of the sole may be cemented to the bottom of the last. It is preferred, however, to secure the sole to the bottom of the last at contiguous points distributed over the entire contacting surface of the sole and last. This manner of securing the sole to the bottom of the last forms an important feature of the present invention.

In its broadest aspects the invention contemplates interposing the adhesive between the sole and the bottom of the last in any suitable manner found desirable or expedient. For economic reasons it is preferred 70 to interpose a carrier of the adhesive between the sole and the bottom of the last as the proper amount of adhesive may be loaded on the carrier to make a good joint without waste.

Heretofore in preparing soles for the shoe bottoming operations it has been the practice to roughly die out the soles and then bring them to the required shape in a rounding machine before they are secured to the bottom of the last. With this method variations occur in the sole which prevent its proper fitting to the last bottom. I propose to prevent the development of variations in the sole by securing the roughly 80 died out sole upon the bottom of the last and then trimming the sole to the edge of the last bottom while secured thereon. This method produces a good fitting sole and eliminates one operation in the manufacture 85 of welt shoes.

Other features of the invention consist in certain methods, combinations and arrangements of parts fully set forth hereinafter, the advantages of which will be readily 90 understood by those skilled in the art.

The various features of the present invention will be readily understood from an inspection of the accompanying drawings, in which,

Figure 1 is an elevation showing the adhesive carrier interposed between the sole and the bottom of the last;

Fig. 2 is an elevation showing the sole secured to the bottom of the last;

Fig. 3 is a plan of the roughly died out sole; and

Fig. 4 is a plan of a sole trimmed to the edge of the last.

5 In the illustrated embodiment of the invention the roughly died out sole 1 which is to be secured to the bottom of a last 2 is first provided with a coat of shellac and is then tempered by immersion in water. The 10 shellac prevents the wetting of the grain side of the sole which is the side exposed in the finished shoe.

The adhesive employed to secure the sole to the bottom of the last is paraffin. In order 15 to introduce the paraffin between the sole and last in a quantity sufficient to make a good joint without waste the paraffin is carried by a sheet of surgeon's gauze or cheese cloth 3. The gauze is carried in a 20 roll 4 rotatably mounted on a bracket 5 conveniently positioned near the operating point. A portion of the gauze is drawn from the roll and passed between a pair of rolls 6 and 7 into a bath 8 containing the 25 hot paraffin. From the bath 8 the gauze passes between the roll 7 and a third roll 9 which strips the gauze of superfluous adhesive. The gauze loaded with the adhesive is then placed in position on the bottom of 30 the last.

The roughly died out sole is now placed in position over the gauze and pressed down thereon. Preferably the sole pressing operation is performed in a sole laying machine which is provided with a laying pad such as disclosed in application for Letters 35 Patent of the United States, Serial No. 789,325, filed by me September 11, 1913.

After the roughly died out sole is set in 40 position on the last bottom the projecting margins of the sole and gauze are trimmed to the edge of the supporting last. Obviously this manner of rounding the sole must be productive of a sole which accurately 45 fits the bottom of the last.

The sole may be stripped from the last at any time after the sewing operation. Preferably the sole and last are separated prior to the heelng operation as the shoe is heated to dry the outsole in preparation for this operation and advantage may be taken of this heating of the shoe to melt the paraffin sufficiently to separate the sole and last.

It will be readily understood that any 55 adhesive material may be employed for securing the insole to the last bottom. I prefer to use paraffin as it has the properties of forming a thin film upon the gauze and of quickly setting. In fact the laying of the 60 sole upon the paraffin chills it sufficiently to make the operations of attaching and setting the sole upon the last bottom substantially simultaneous. Obviously paraffin is an economic material to use. The use of 65 paraffin also permits the last and sole to

pass directly to the next operating station as an intermediate drying operation is not necessary.

While the illustrated embodiment of the present invention is directed to a method 70 for use in making the shoe devised by me, it will be apparent to those skilled in the art that the methods herein disclosed may be advantageously employed in the manufacture of other kinds of shoes, such for 75 instance, as turns, McKays and Goodyears.

The operations which are performed as above described and illustrated are those which are preferred in practising the present invention. It is to be understood, however, that except as defined in the claims the invention is not limited to the precise methods illustrated and described and that the steps of the method may be varied or modified without departing from the spirit 85 of the invention.

What is claimed as new, is:—

1. That improvement in the art of securing soles to lasts which consists in placing an adhesive carrier on the bottom of the last 90 and pressing a sole upon the adhesive carrier to join the sole to the last, substantially as described.

2. That improvement in the art of securing soles to lasts which consists in loading a 95 carrier with the proper amount of adhesive to make a good joint without waste, placing the loaded carrier upon the bottom of the last, and pressing a sole upon the carrier to join the sole to the last, substantially as described.

3. That improvement in the art of securing soles to lasts which consists in saturating a sheet of fabric with an adhesive, placing the saturated sheet upon the bottom 105 of a last, and pressing a sole upon the sheet to join the sole to the last, substantially as described.

4. That improvement in the art of securing soles to lasts which consists in interposing between the sole and the bottom of the last a sheet of fabric saturated with an adhesive, and pressing the sole, sheet and last together, substantially as described.

5. That improvement in the art of preparing soles for the shoe bottoming operations which consists in roughly dieing out the sole, placing a sheet of fabric saturated with an adhesive upon the bottom of a last, pressing the roughly died out sole upon the 115 sheet of fabric to join the sole to the last, and trimming the projecting margins of the sole and sheet of fabric on the bottom of the last to the edge thereof, substantially as described.

6. A step product of the last and sole assembling operation in the manufacture of a shoe comprising a last and a sole secured to the bottom of the last by an adhesive.

7. A step product of the last and sole as 130

sembling operation in the manufacture of a shoe comprising a last and a sole secured to the bottom of the last by paraffin.

8. A step product of the last and sole assembling operation in the manufacture of a shoe comprising a last, a sole, and a sheet of fabric saturated with an adhesive securing the sole to the last.

9. A step product of the last and sole assembling operation in the manufacture of

a shoe comprising a last, a sole, and a sheet of fabric saturated with paraffin securing the sole to the last.

10. A step product of the last and sole assembling operation in the manufacture of a shoe comprising a last and a sole secured thereto by a fastening means which prevents the buckling of the margin of the sole under the strains of the lasting operation.

CHARLES C. BLAKE.
